John Tjaarda, Detroit, Mich., assignor to Briggs Manufacturing Company, Detroit, Mich., a corporation of Michigan

Application May 3, 1939, Serial No. 84,772

Term of patent 14 years

To all whom it may concern:

Be it known that I, John Tjaarda, a subject of the Netherlands, residing at Detroit, county of Wayne, State of Michigan, have invented a new, original, and ornamental Design for a Combination Kitchen Unit, of which the following is a specification, reference being had therein to the accompanying drawing, forming a part thereof, in which

Fig. 1 is a perspective view looking toward the front of the unit from the right side thereof; and
front of the unit from the left side thereof.

I claim:

The ornamental design for a combination kitchen unit, substantially as shown.

JOHN TJAARDA.
